UNITED STATES PATENT OFFICE

1,924,127

APPARATUS FOR PRODUCTION OF OXIDES

Emil M. Lofland, Chicago, Ill.

Application June 7, 1928. Serial No. 283,607

2 Claims. (Cl. 23—285)

This invention relates to metallurgical apparatus such as is adapted for use in processes like that described in my U. S. Letters Patent No. 1,689,951, granted October 30, 1928. In certain particulars the present invention is an improvement upon the apparatus disclosed and claimed in my copending application Serial No. 273,838, filed April 30, 1928.

A general object of the present invention is the provision of an apparatus whereby oxides and hydrates may be rapidly produced and recovered from metals under controlled conditions.

A particular object is the provision of such apparatus whereby the oxide or hydrate may be recovered from the metal in only partly oxidized condition, as for example the recovery of a hydrous ferrous oxide from iron before it has been converted to a ferric condition.

Yet another object is the provision of an apparatus which may be definitely controlled in operation, which is of strong and simple construction and which is productive of a large output.

Other and further objects will be pointed out or indicated hereinafter or will be apparent to one skilled in the art upon an understanding of the invention or its employment in practice.

For the purpose of aiding in the disclosure of the invention I illustrate in the accompanying drawings forming a part of this specification, one form of apparatus embodying the same, but it is to be understood that the invention is not limited to this particular construction or arrangement.

In the drawings,

Fig. 1 is a diagram showing in transverse sectional elevation, an apparatus embodying the principles of the invention;

Fig. 2 is a side elevation, on a larger scale, of a portion of one of the agitators involved in the apparatus shown in Fig. 1;

Fig. 3 is a transverse, vertical section on line 6—6 in Fig. 2;

Fig. 4 is a plan of the apparatus shown in Fig. 1, with certain portions thereof broken away for convenience of illustration;

Fig. 5 is an enlarged section on line 8—8 in Fig. 4, with certain portions thereof broken away for convenience of illustration; and

Fig. 6 is an enlarged vertical section on line 9—9 in Fig. 5, showing certain portions broken away for convenience of illustration.

An understanding of the invention may be had quite quickly by reference to the embodiment illustrated in the drawings.

As thus illustrated, the apparatus shown in

Fig. 1 comprises an agitating and reaction basin 1 adapted to contain a bed of iron borings supported on its sloping bottom. Tracks 2 and 3 are provided at opposite sides of this basin, upon which the wheels 4 of the carriage 5 are adapted to run and permit the carriage to travel back and forth. This carriage carries a rotary agitator shaft 5 having the agitating arms 6 for plowing up and disturbing and agitating the iron borings held in the basin. The frame of the carriage carries an electric motor 7, which is connected by gearing 8, 9, 10, 11 and 12 with the agitator shaft 5 previously mentioned, thereby to rotate this shaft. A hopper 13 is provided on the carriage for a supply of the iron borings, and a screw conveyor 14 is provided in a tubular housing 15, which is connected by the passage 16 with the said hopper. The lower side of the housing 15 is provided with valved discharge outlets 17 for discharging the iron borings downwardly upon the agitators and into the basin. An electric motor 18 may be provided and geared to one or more of the wheels 4, and controlled in any suitable manner to propel the carriage back and forth across the agitating and reaction basin. Any suitable connection can be provided between one of the motors and the screw conveyor 14, to drive the latter in the desired manner. A solution of any acid or acid salt (ferrous sulphate) may be taken from a suitable source of supply through a pipe 20 into the intake of the pump 21 and discharged from the latter through the pipe 22 into the spraying pipes or distributors 23, which latter are disposed in position and have orifices 24 on their lower sides to discharge the solution downwardly upon the agitators and the iron borings in the manner illustrated in Fig. 6 of the drawings. The said pump 21 and pipes leading thereto and therefrom are suitably mounted upon the carriage 5 and travel therewith. The source from which the liquid is drawn by the pump 21 may be in the form of a trough 19 extending alongside the basin so that the pipe 20 may travel in the same as the carriage moves along. In this way, and in whatever position the carriage may occupy over the agitating and reaction basin, the pipe 20 will always be in position to draw solution from the open trough 19.

Pipes 26 and 27 form conduits for connecting the collecting troughs 28 and 29 with the hydrate sump 30, which latter is of any suitable character. Thus the ferrous hydrate formed on and removed from the iron borings and flushed out by the liquid will be discharged into the said sump 30 after it has been flushed from the agitating and

reaction basin 1 and into the launder troughs 28 and 29.

From the said sump 30 the hydrate and the carrying liquid may be pumped to a thickener in 5 which the greater portion of the liquid may be separated from the hydrate and returned by way of 39 to the trough 19, so that any excess of the solution may be returned from the thickener for re-use in the agitating and reaction basin.

10 The hydrate, as explained in my patent above identified, is produced on the borings by subjecting the iron borings, or other metal, or metal in similar or other form, when properly wetted with a solution of a suitable acid or acid salt (ferrous 15 sulphate) to the action of oxygen (as in air) for a definite period of time in the agitating and reaction basin. The bluish-green ferrous hydrate is formed as a coating on each particle, large or small, of the iron borings, and is separated therefrom by the periodical agitating and flushing operations performed by the agitators and distributor incident to travel of the carriage back and forth across the agitating and reaction basin. Then, as previously explained, the ferrous 20 hydrate separated from the borings is carried by the overflow of the washing solution to a recovery system by the operation of which the ferrous hydrate is reclaimed as a sludge, as in the said thickener, and the excess solution may be then 25 returned and again used for wetting and flushing the bed. The iron borings, after each agitating and flushing operation, are no longer coated with ferrous hydrate, but are covered with a thin film of acid solution. The iron borings when in this 30 condition are again subjected to the action of oxygen for the required period of time, during which additional hydrate is formed on them, which is likewise separated and similarly recovered. In this way the production of the ferrous hydrate is made continuous, these washing and agitating steps being so controlled that 35 ferrous hydrate is being continuously separated and recovered from borings in a portion of the bed, while those in the other portions are being subjected to chemical reaction in a quiet condition. The continuity of production of the ferrous hydrate is also maintained by replenishing the bed with fresh borings from time to time by 40 means of the conveyor 14.

45 As shown in Figs. 1 and 5 of the drawings, it will be seen that the bottom of basin 1 slopes to the left, so that the solution in the basin will flow by gravity into the launder troughs 28 and 29. The jets from the pipes 23 impinge on the 50 borings adjacent the agitator, and the rotation of the agitator will tend to form a trench in the

bed, and the solution will tend to follow this trench and discharge into the troughs 28 and 29, as explained. It will be seen that the walls at each side of the trough 29 are notched to provide spaced openings 60, as shown in Fig. 4 of the drawings, and the inside wall of the trough 28 is also similarly notched or cut away at intervals to provide the openings 61, these openings being preferably provided with screen material of some kind to keep the iron borings from falling out, but permitting the hydrate to flow into the troughs 28 and 29 in the manner described. By using an agitating and reaction basin of this form, in combination with an agitator that is mounted to travel back and forth above the basin, it is obvious that the basin can be enlarged from time to time by adding on to either end thereof, as the crane supporting the agitators can travel any desired distance, and can operate over a long basin as well as over a short 95 basin.

As shown in Fig. 6 of the drawings, inclined pipes forming nozzles can be attached to the tubes 23, to receive the solution from the openings 24, if such is necessary or desirable. The pipes for this purpose are indicated in dotted lines in Fig. 6 of the drawings.

I claim:

1. Apparatus for controlling production of oxides comprising, in combination, a basin arranged to support a bed of fragmentary material, said basin having a bottom sloping toward one side, a carriage mounted to travel back and forth over the basin in directions parallel with said side, a trough along said side of the basin for reception of material flushed therefrom, an agitator operably mounted on the carriage for rotation on an axis extending substantially at right angles to said side of the basin, means for propelling the carriage and actuating the agitator, and means for flushing the bed.

2. Apparatus for the production of hydrous oxides comprising, in combination, a basin having a draining bottom, a carriage arranged to travel back and forth over the basin, an agitator carried by said carriage for operation in the basin, means for actuating the agitator and propelling the carriage, a distributor arranged to shower liquid into the basin in proximity to the agitator, a liquid container arranged alongside the basin, and a pump carried on the carriage and having an inlet for taking liquid from said container and having outlet connection with the distributor.
